Attorney, Agent, or Firm—Mark Rogers; Gary N. Speed

[57] CLAIM

The ornamental design for a folding table, as shown and described.

DESCRIPTION

FIG. 1 is a perspective view of the folding table showing our new design in the deployed position;

FIG. 2 is a front elevational view thereof in the deployed position;

FIG. 3 is a side of elevational view taken from the right side thereof in the deployed position;

FIG. 4 is a rear elevational view in the deployed position;

FIG. 5 is a side elevational view taken from the left side thereof in the deployed position;

FIG. 6 is a top plan view thereof in the deployed position;

FIG. 7 is a bottom plan view thereof in the deployed position;

FIG. 8 is a perspective view of the folding table showing our new design in the folded position;

FIG. 9 is a front elevational view thereof in the folded position;

FIG. 10 is a side of elevational view taken from the right side thereof in the folded position;

FIG. 11 is a bottom plan view thereof in the folded position; and,

FIG. 12 is a top plan view thereof in the folded position.
